His Attorney.

UNITED STATES PATENT OFFICE

CHARLES L. HEISLER, OF SCHENECTADY, NEW YORK, ASSIGNOR TO GENERAL ELECTRIC COMPANY, A CORPORATION OF NEW YORK

REFRIGERATING APPARATUS

Application filed April 22, 1927. Serial No. 185,849.

My invention relates to refrigerating apparatus and particularly to the cooling unit of refrigerating apparatus of that type especially adapted for domestic use. It is an object of my invention to provide an improved cooling unit which in construction is simple and well adapted for use in domestic refrigerating apparatus and is durable and efficient in operation.

10 My invention will be better understood from the following description taken in connection with the accompanying drawing, and its scope will be pointed out in the appended claims.

15 Referring to the drawing, Fig. 1 represents in section a refrigerating apparatus having a cooling unit involving my invention; Fig. 2 is an elevation of the cooling unit partly in cross section; Figs. 3 and 4 show 20 respectively the upper and lower cooling coils of the cooling unit; Fig. 5 is a detail of the valve mechanism and Fig. 6 illustrates a modification.

In Fig. 1 of the drawing I have shown, by 25 way of example, only a refrigerating apparatus of the domestic type comprising the box 1 having the compartment 2 for receiving food, etc., and the refrigerator cooling unit 3. Below the compartment 2 I have 30 shown mechanism 4 for compressing and cooling the refrigerant. This mechanism may be of any desired construction and may be located above the compartment 2 instead of below it if desired.

35 Referring now to Fig. 2 the cooling unit 3 comprises an outer casing 5, preferably circular, and shown as formed of interfitting upper and lower members 6 and 7 and an inner casing 8 preferably rectangular, the 40 walls of which are spaced from the walls of the outer casing. The inner casing 8 is open to the exterior at one end at least and is adapted to receive material to be frozen or cooled to a lower temperature than exists outside of the cooling unit. I have shown for 45 example trays 10 in the inner casing which may be provided with partitions for the purpose of freezing ice cubes. I construct the bottom 11 of the outer casing to slope downward to a common point, the bottom being

illustrated as conical, whereby during the defrosting of the cooling unit the water will follow the slope and drip from a single point. A small shallow receptacle only is necessary to collect the drip and this I have shown at 12 mounted on the stud 13 below the apex of the cone. For draining the receptacle 12 I have shown the waste pipe 14 which may be arranged to connect with a sewer. Between the inner and outer casings 55 of the cooling unit I arrange the evaporator comprising cooling elements 15 and 16 each shown as comprising a pipe having a plurality of loops or turns termed a coil, the former arranged above and the latter arranged below the inner casing. Inasmuch as the evaporator which I have illustrated is of the "flooded" type the two ends of each cooling element connect with the header 17 at 60 vertically spaced points. The two cooling 70 elements preferably comprise substantially flat horizontal coils, care being taken in their construction that pockets are not formed that will collect gas and prevent free circulation of the liquid refrigerant therein. Upper 75 coil 15 has formed therein a riser 18, the lower end of which connects with the lower portion of the header through a material portion of the coil, shown as approximately one half turn. Similarly the lower coil 16 has 80 a riser 19 by which it connects directly with the upper portion of the header. As a result of this construction the gas bubbles due to the evaporation of the refrigerant in the coils produce a rapid circulation of the refrigerant in the coils thereby greatly increasing the efficiency of the evaporator.

Another important feature in my cooling unit is the construction whereby the cooling effect of the coils is concentrated on the inner casing enabling ice cubes for example to be frozen in a much shorter time than is usual with cooling units in apparatus of this type. I accomplish this in part by placing the upper and lower coils in good thermal connection with the respective upper and lower walls of the inner casing 8, preferably in actual contact therewith. In the space between the two casings I have shown a liquid 90 95 100 20, as for example brine or a mixture of

glycerine and water, which acts as a heat reservoir and assists in the transfer of heat to the coils. I have found that the cooling effect of the coils may be still further concentrated upon the inner casing by retarding the otherwise free circulation of the liquid relative to the cooling coils. For this purpose I have shown a baffle 22 immersed in the liquid 20 and supported close to each coil 10 and at the side thereof opposite the inner casing. The extent and position of the baffles relative to the cooling coils will be governed by the relative amounts of refrigeration desired in the inner receptacle 8 and in 15 the main food chamber 2. If desired the baffles may be provided with openings to allow a limited amount of circulation of the liquid 20 therethrough.

In the header 17 I have shown a float 23 20 which connects through suitable lever mechanism with the valve 24, shown in detail in Fig. 5, for controlling the flow of liquid refrigerant into the header through inlet pipe 25 and screen 26 to maintain a constant level 25 in the header. Outlet pipe 27 having an open upper end projects into the space above the level of the liquid refrigerant and connects with the intake of the compressor. The upper end of the pipe 27 is shown having a 30 narrow slot 28 through which lubricating oil, shown on the surface of the liquid refrigerant, may escape slowly when the level thereof exceeds a certain height. Below the header 17 I have shown a drip receptacle 29 which also 35 connects with the waste pipe 14. For supporting the cooling unit I have shown the top provided with loops 30 which may engage suitable hooks in the top of the chamber 2.

In the modification shown in Fig. 6 I have 40 mounted the header within the cooling unit, the upper end only projecting out of the top, the construction otherwise being similar to that shown in Fig. 2, except of course that a separate drip receptacle is unnecessary.

45 I have chosen the particular embodiments described above as illustrative of my invention and it will be apparent that various other modifications may be made without departing from the spirit and scope of my invention 50 which modifications I aim to cover by the appended claims.

What I claim as new and desire to secure by Letters Patent of the United States is:

1. A refrigerator cooling unit comprising 55 spaced inner and outer casings, said inner casing forming a receptacle adapted to receive material to be frozen, a liquid in the space between said casings, means for conducting refrigerant through said liquid and 60 means immersed in said liquid tending to confine the liquid cooled by the refrigerant toward the walls of the inner casing.

2. A refrigerator cooling unit comprising 65 an outer casing, an inner casing forming a receptacle adapted to receive material to be

frozen, a liquid in the space between said casings, refrigerant conducting means in the space between the casings arranged in good thermal connection with the inner receptacle, and means immersed in said liquid for thermally isolating said conducting means from the outer casing. 70

3. A refrigerator cooling unit comprising 75 an outer casing containing a liquid, an inner casing forming a receptacle adapted to receive material to be frozen, means arranged in the space between the casings and close to the inner casing for conveying liquid refrigerant and a baffle arranged at the side of said means opposite said inner casing. 80

4. A refrigerator cooling unit comprising 85 an outer casing adapted to contain a liquid, an inner casing forming a receptacle adapted to receive material to be frozen, a coil for refrigerant arranged between the casings and close to the inner casing, and a baffle for retarding the circulation of said liquid toward the walls of the outer casing. 95

5. A refrigerator cooling unit comprising 90 an outer casing, an inner casing forming a receptacle for material to be frozen, a header containing liquid refrigerant and a substantially horizontal cooling coil having its ends connected at vertically spaced points with said header and arranged between the casings. 95

6. A refrigerator cooling unit comprising 100 an outer casing containing a liquid, an inner casing forming a receptacle for material to be frozen, a header containing liquid refrigerant, a substantially horizontal cooling coil having its ends connected at vertically spaced points with said header, said coil being arranged between said casings and in good thermal connection with a wall of the inner 105 casing, and means for retarding the circulation of the liquid cooled by said coil.

7. A refrigerator cooling unit comprising 110 an outer casing containing a liquid, an inner casing forming a receptacle for material to be frozen having substantially flat top and bottom walls, a header containing liquid refrigerant, and substantially flat cooling coils in said liquid in good thermal connection with each of said walls, said coils having their ends connected with said header at vertically spaced points. 115

8. A refrigerator cooling unit comprising 120 an outer casing, an inner casing spaced there-in and forming a receptacle for material to be frozen, a header, and a cooling coil having its ends connected with the header at spaced points, said header and cooling coil being arranged in the space between the inner and outer casings. 125

9. A refrigerator cooling unit comprising 130 a header, a substantially horizontal cooling coil comprising a plurality of loops, the ends of the coil being connected with the header at vertically spaced points thereof, and means

for maintaining liquid refrigerant in the header at a level above both connections therewith of the cooling coil, whereby a rapid circulation of liquid refrigerant is induced

5 in the coil.

10. A refrigerator cooling unit comprising a header, and a substantially horizontal cooling coil comprising a plurality of loops, the ends of the coil having connections with the header at vertically spaced points thereof, said coil having a riser therein separated from the lower connection with the header by a material portion of the coil.

15 In witness whereof, I have hereunto set my hand this 20th day of April, 1927.

CHARLES L. HEISLER.
